MAIL CRANE AND MEANS FOR OPERATING
THE SAME

Garrett J. Barry, Toledo, Ohio

Application July 9, 1937, Serial No. 152,789

3 Claims. (Cl. 258—8)

This invention relates to mail cranes, and has for its general object to provide a crane of this character which may be conveniently operated from a moving mail car to automatically bring a mail bag on said crane into operative relation to the catcher with which such cars are ordinarily provided. A further object of the invention is to provide a crane of this character which is generally efficient in operation and which can be conveniently reset after having been operated.

The invention herein constitutes an improvement over that disclosed in my Patent No. 1,360,354 issued November 30, 1920, in respect to the particular means for operating the mail crane shown in said patent, and more particularly in respect to insuring the efficient operation of the said crane in order to bring the mail sack in operative relation to the standard catcher, notwithstanding the fact that the train carrying the mail car may be proceeding at a very high rate of speed.

Further objects of the invention will be realized in and through the construction and arrangement of the parts illustrated in the drawings hereof, wherein Fig. 1 shows in dot-and-dash lines the engine and tender of a locomotive and the manner in which my invention is adapted to cooperate with the standard mail car equipment; Fig. 2 a sectional plan view of the mail crane and part of the connections for automatically operating the same; Fig. 3 a vertical sectional elevation of the mail crane and a portion of the connections for automatically operating the same; Figs. 4 and 5 are sectional elevations; and Fig. 6 a detail in section, of the mechanism for rotating and locking the mail crane shaft; and Figs. 7 and 8 are details in perspective of the mechanism for rotating the said mail crane shaft.

The complete mechanism includes a rotary mail crane shaft having the usual arms for supporting a mail bag, means tending to rotate the said shaft to bring a mail bag on said arm in operative relation to a catcher on a mail car, a locking device normally preventing the rotation of said shaft, and means operative by the front wheels of the engine for disengaging the said locking device thereby to enable the shaft to be rotated to bring the mail bag in operative relation to said catcher.

In the drawings forming part hereof, 1 represents one of the rails of a track, 20 an engine and 20^a the tender thereof. 21 denotes a vertical housing shown as supported on an exten-

sion of one of the cross ties, said housing having a door 22 which may be provided with a lock to permit access to and prevent tampering with the parts therein. The particular cross tie illustrated herein may be a metal channel having its flanges 23 extending downwardly and its web 24 providing a cover for the operating lever therebeneath. A plate 25 is shown as extending transversely of the housing 21 and will be secured to the same in any suitable manner, as by welding, where the housing is of metal. Extending through a central aperture in the plate 25 is the vertical crane shaft 26, said shaft extending through the coverplate 21^a of said housing and being provided with the usual arms 27 and 28 for supporting a mail bag, indicated at 29 on Fig. 1. The arm 27 is pivoted to a yoke on the top of the crane shaft and is counterbalanced to cause it to assume a vertical position when relieved of the weight of the bag. The arm 28 is pivoted so that it can drop to a vertical position by gravity when the mail bag is disconnected therefrom by the catcher. The construction of the arms 27 and 28 is that ordinarily employed with mail cranes and in its details, forms no part of my invention.

Suitably secured to the plate 25, as by lag screws 30, is a sleeved supporting member 31 having vertically extending stop projections 32 and 33 and a spiral track 33^a extending between said projections. Rigid with the shaft 26 is a cooperating member 34 having a hub portion 35 carrying a spiral rib 36 one end 37 whereof, cooperates with the stop projection 32, and the other end whereof cooperates with the stop projection 33. The lower surface of the rib 36 is inclined complementarily to the inclination of the track 33, there being rollers 38 mounted in recesses provided in the lower surface of the rib 36, said rollers moving along the track 33^a. 39 denotes a cup which is adjustable along the shaft 26 by means of a nut 40 threaded on the lower end of said shaft, there being a lock nut 41 below the nut 40 for the purpose of retaining the latter, and the cup 39 in any position to which they may be adjusted. Surrounding the lower portion of the shaft 26 is a strong helical spring 42, the lower end whereof extends within the cup 39 and is connected to the shaft, the upper end of said spring engaging a lug 43 projecting downwardly from the plate 25.

On the upper surface of the rib 36 is a locking projection 36^a extending transversely of said rib and being angular in outline. The lower end 55

of said rib constitutes a stop projection which cooperates with the projection 32.

Secured to the plate 25 at one side of the members 31 and 34 is a block 44. The face of this block which is presented toward the members 31 and 34 is concave. Extending through said block are rods 45, said rods being threaded and provided with nuts 46 to secure them in position and to clamp the block to the plate 25, the upper ends of the rods projecting through the head plate 47 having a central aperture for the upper end of a rod 48 having a collar 49 thereon above said block, there being a helical spring 50 interposed between said collar and the plate 47. The portion of the rod 48 which extends through the block 44 is preferably angular in section and slides within a similarly shaped bore through said block, whereby the rod may reciprocate with respect to said block without rotating. Projecting from the rod 48 above the block is a locking dog 51 adapted to overhang the rib 36 and having an angular notch 52 therein adapted to receive the angular locking projection 36^a on said rib and thereby prevent the rotation of the shaft 26 by the spring 42.

The rod 48 is preferably made in two parts having reversely threaded ends connected by a correspondingly threaded sleeve 53, enabling the effective length of said rod to be varied. The lower end of the rod projects through an opening in the web 24 and is connected to one arm 54 of a bell crank lever, the other arm 55 of said lever being connected to a link 56, the pivot for the bell crank lever being indicated at 54^a. The opposite end of the link is in turn connected to one arm 57 of a bell crank lever, the other arm 58 whereof is connected to a long link or rod 59. The pivot for the second bell crank lever is indicated at 57^a. The rod or link 59 extends forwardly from the cross tie 23, 24, being arranged in close proximity to the rail 1 and conveniently and slidably supported by sleeves 60 carried by the cross ties 61. At its forward end it is connected to the lower end of a lever 62, pivotally supported at 63, the upper end 64 of the lever extending adjacent to and preferably a short distance above the rail 1, where it will be engaged by the flange on the front wheel of the locomotive. The pivot 63 is conveniently supported by brackets 63^a which may be carried by a cross tie; and the rod or link 59 and the sleeves 60 will, in common practice, be enclosed within a suitable casting.

With the parts constructed and arranged as described, the operation will be as follows:

The mail crane shaft having been set and locked with its arms 27 and 28 projecting parallel with the track, as by means of the hand wheel 65, and a mail bag having been applied to said arms in the usual manner, the operator on the mail car will set his catcher in the usual position to receive the mail bag. When the locomotive of the train carrying the mail car advances slightly beyond the position shown in Fig. 1 the upper arm of the lever 62, 64 will be rocked forwardly, thereby moving the rod or link 59 rearwardly and, through the bell crank lever 57, 58, link 56 and bell crank lever 54, 55, will lift the rod 48, thereby to release the dog 51 from the locking projection 36^a. Immediately upon the release of the dog, the spring 42, having been set under strong compression, will rotate the shaft 26 rapidly toward the tender 20^a, until the shaft is given a rotation of about 90° in this di-

rection, its rotation being stopped by the projection 32.

It will be noted that the length of the rod or link 59 is such as to enable the engine cab to pass the mail crane before the lever 62, 64 is operated to cause the spring 42 to rotate the shaft 26 toward the crane. This avoids any liability of the engineer or fireman being struck by the mail bag or the arms of the crane. Furthermore, where the mail car is immediately at the rear of the tender, the distance which the train must travel, after the release of the dog 51 from the locking projection 36^a, before the door of the mail car reaches the mail crane will be ample to enable the shaft 26 to rotate the desired distance to enable the catcher to engage and remove the mail bag. The speedy rotation of the mail crane shaft is insured by the strength of the spring 42 and the steep pitch of the track 33^a and the use of the anti-friction rollers 38.

Having thus described my invention, what I claim is:

1. The combination, with a track, of a rotatable mail crane shaft, means tending to rotate said shaft, a locking member carried by said shaft, a rod extending parallel with said shaft and having a locking member cooperating with the first mentioned locking member, yielding means tending to hold said locking members in engagement, and means operable by a wheel of a locomotive traveling along said track for moving said rod, thereby to disengage its locking member from the first mentioned locking member, the said means comprising a lever pivoted intermediate of its ends and having its upper end positioned to be engaged and moved forwardly by a front wheel of said locomotive when the said shaft is at the rear of the cab of said locomotive, a rod connected to the lower end of said lever and extending rearwardly therefrom, a bell crank lever having one arm connected to the rear end of the second rod, a link connected to the other arm of said bell crank lever, and a bell crank lever having one arm connected to the first mentioned rod and its opposite end connected to said link.

2. The combination, with a track, of a rotatable mail crane shaft, means tending to rotate said shaft, a locking member carried by said shaft, a locking member cooperating with the first mentioned locking member, yielding means tending to hold said locking members in engagement, and means operable by a wheel of a locomotive traveling along said track for disengaging said locking members, the said means comprising a lever pivoted intermediate of its ends and having its upper end positioned to be engaged and moved forwardly by a front wheel of said locomotive when the said shaft is at the rear of the cab of said locomotive, a rod connected to the lower end of said lever and extending rearwardly therefrom, a bell crank lever having one arm connected to the rear end of said rod, a link connected to the other arm of said bell crank lever, and a bell crank lever having one arm operatively connected to one of the locking members and its opposite end connected to said link.

3. The combination, with a track, of a rotatable mail crane shaft, means tending to rotate said shaft, a locking member carried by said shaft, a rod extending parallel with said shaft and having a locking member cooperating with the first mentioned locking member, yielding means tending to hold said locking members in engagement, and means operable by a wheel of a locomotive

traveling along said track for moving said rod thereby to disengage its locking member from the first mentioned locking member, the said means comprising a lever located adjacent to said track and adapted to be engaged and depressed by a front wheel of the said locomotive when the said shaft is at the rear of the cab of said locomotive, a bell crank lever located adjacent to the

said mail crane, a connection between the first lever and one arm of said bell crank lever, a second bell crank lever having one end operatively connected to one of said members, and a connection between the second arms of the said bell 5 crank levers.

GARRETT J. BARRY.
